United States Patent

Des. 237,422
Patented Oct. 28, 1975

237,422

CARPET

Jon Blumenaus, 113 Tibbs Road,
Dalton, Ga. 30720

Filed Jan. 10, 1974, Ser. No. 432,310

Term of patent 14 years

Int. Cl. D6—11

U.S. Cl. D92—4 R

The single figure of the drawing is a plan view of a carpet showing my new design, a design unit being marked off in dash dot lines.

I claim:

The ornamental design for a carpet, as shown and described.
